SUCTION NOZZLE

Eric Edström, Stockholm, Sweden, assignor to
 Electrolux Corporation, Dover, Del., a corpora-
 tion of Delaware

Application June 26, 1936, Serial No. 87,397
 In Switzerland July 2, 1935

7 Claims. (Cl. 15—155)

My invention relates to suction nozzles for use in connection with a vacuum cleaner and particularly to duplex nozzles provided with openings of different sizes which may be selectively connected to the source of suction. When the larger opening is in use it will cover a larger surface, thereby increasing the speed of cleaning. However, if a concentrated suction is desired in order to remove dirt which the larger opening will not pick up, the smaller opening may be brought into use.

The objects and advantages of my invention will be apparent from the following description considered in connection with the accompanying drawing which forms part of this specification, and of which:

Fig. 1 is a front view, partially in cross section of a preferred embodiment of my invention;

Fig. 2 is a cross-sectional view taken on the line 2—2 of Fig. 1; and

Fig. 3 is a bottom view of the nozzle shown in Figs. 1 and 2.

Referring to the figures, reference character 10 designates a nozzle body formed with an elongated portion 11, and a cylindrical portion 12. The portion 11 defines an elongated suction opening 13 divided into three sections by means of transverse partitions 14. A slot 15 provides communication between the interior of cylindrical portion 12 and all three of the sections of the elongated opening 13.

Rotatively mounted within cylindrical portion 12 is a cylindrical valve member 16 formed with a long slot 17 and a shorter slot 18. Slot 17 is of substantially the same length as the entire length of slot 15, while slot 18 is of a length not greater than the distance between partitions 14. Rigidly secured to valve member 16 and communicating with the interior of cylindrical portion 12 is a hollow member 19 adapted to have secured therein a conduit member 20 connected with a source of suction. Hollow member 19 extends through an opening 21 in the upper part of cylindrical member 12, which opening permits and limits rotation of the valve member 16.

With the parts in the position shown in Figs. 1 and 3, and in full lines of Fig. 2, the long slot 17 is in alignment with the slot 15, whereby air is drawn in through all three sections of the nozzle opening 13. However, should it be desired to employ a more concentrated suction, conduit member 20 is pivoted to the position shown in dash and dot lines in Fig. 2, thereby rotating valve member 16 to a position so that the short slot 18 is in alignment with slot 15. However,

the length of slot 18 is such that it establishes communication between only the central section of suction opening 13 bounded by walls 14 and the interior of the valve member. Consequently, all of the air drawn into the nozzle must pass through this central section of the suction opening, whereby a concentrated flow at this point is obtained.

While I have shown and described one more or less specific embodiment of my invention it is to be understood that this has been done for purposes of illustration only, and that the scope of the invention is not to be limited thereby, but is to be determined by the appended claims viewed in the light of the prior art.

What I claim is:

1. In a suction nozzle, a hollow body defining a suction opening divided into a plurality of sections, a cylindrical valve member rotatably mounted in said body and formed with one port adapted to communicate with all of said sections and with another port adapted to communicate with only one of said sections, and means for connecting a suction conduit to said valve member, said valve member being rotatable by said conduit to bring either of said ports into operative position.
2. In a suction nozzle, a hollow body defining an elongated suction opening, means dividing said opening into a plurality of longitudinally aligned sections, said nozzle being formed with an outlet opening adapted to be connected to a source of suction, and means for connecting all of said sections simultaneously to said outlet opening and selectively for disconnecting sufficient of said sections so that the remainder of said sections occupies less than half of said suction opening.
3. In a suction nozzle, a hollow body defining an elongated suction opening, means dividing said opening into a central and two end sections, all of said sections being disposed in longitudinal alignment, said nozzle being formed with an outlet opening adapted to be connected to a source of suction, and valve means for connecting all of said sections to said outlet opening and selectively for connecting only said central section to said outlet opening.
4. In a suction nozzle, a body defining an elongated suction opening, means dividing said opening into a central and two end sections, all of said sections being disposed in longitudinal alignment, a valve member rotatably mounted in said body, and a suction conduit connectable to said valve member, said valve member being rotatable

by said conduit for connecting all of said sections to said conduit and selectively for connecting only said central section to said conduit.

5. In a suction nozzle, a hollow body defining an elongated suction opening, means dividing said opening into a central and two end sections, all of said sections being disposed in longitudinal alignment, and the central of said sections being of less cross-sectional area than either of the end sections, said nozzle being formed with an outlet opening adapted to be connected to a source of suction, and valve means for connecting all of said sections to said outlet opening and selectively for connecting only said central section to said outlet opening.

6. In a suction nozzle, a hollow body defining an elongated suction opening, means dividing

said opening into a plurality of longitudinally aligned sections, said nozzle being formed with an outlet opening adapted to be connected to a source of suction, and a single valve means for connecting all of said sections to said outlet opening and selectively for connecting only one of said sections to said outlet opening.

7. In a suction nozzle, a hollow body formed with at least three longitudinally aligned suction openings, said nozzle being formed with an outlet opening adapted to be connected to a source of suction, and a single valve means operative to connect all of said suction openings with said outlet opening and selectively to connect only the central of said suction openings with said outlet opening.

ERIC EDSTRÖM.
